UNITED STATES PATENT OFFICE

ARBA G. WILLIAMSON, OF CARNEGIE, PENNSYLVANIA, ASSIGNOR, BY MESNE ASSIGNMENTS, TO THE UNION SWITCH & SIGNAL COMPANY, OF SWISSVALE, PENNSYLVANIA, A CORPORATION OF PENNSYLVANIA

TRACK CIRCUIT SYSTEM

Application filed February 3, 1927. Serial No. 165,603.

This invention relates to track circuit systems particularly for use in connection with train control systems of the type disclosed in Letters Patent No. 1,791,779 of February 5 10, 1931, and the present application is a continuation, in part, of application Ser. No. 549,663 filed April 5, 1922. The combination of trackway means to supply interrupted or periodically varying current in combination 10 with cab equipment controlled by the influence of such current is, however, not claimed herein but forms the subject matter of applicant's copending application Ser. No. 215,318 filed August 25, 1927.

15 In certain train control systems the train is provided with two pick-up circuits one of the indirect type and the other of the direct type and one of the main objects of this invention is to provide means whereby a circuit 20 may be established including both rails of a block and whereby also another circuit may be established between one or both rails and ground to properly coordinate the indirect and direct pick-up circuits on the train with 25 track equipment. A further object of the invention is to provide means whereby the circuit between one rail and ground is so arranged that existing track circuits may be used with but slight alteration. It will be 30 understood, however, that the invention is by no means limited to the above features but contains other and independent features of invention especially in connection with supplying an interrupted current to a traffic 35 track.

Certain features of the invention are claimed in application Ser. No. 549,668 filed April 5, 1922.

In the accompanying drawings the invention 40 is shown diagrammatically in several preferred forms.

Fig. 1 is a diagrammatic view showing one form of the invention.

Figs. 2, 3, 4 and 5 are diagrammatic views 45 showing other forms of the invention.

Referring to Fig. 1, 1 and 2 represent the rails of a traffic track divided into blocks, W, X, Y and Z in a manner well understood as by means of insulation 3. The wayside signals which may or may not be used are in-

dicated by S_x, S_y and S_z and as here shown the track circuits are operated by a direct current supplied by battery 150 connected to the rails by leads 118 and 117, this current normally energizing relay 151 controlling 55 armatures 143 and 152 of the block in rear. The current supplied for influencing the indirect and direct pick-up circuits of the train is supplied by a battery 110 and an interrupter 106 actuated by motor element 107. 60 The interrupted current supplied to the two rails of the track and adapted to influence the indirect pick-up circuit of the train is impressed on the rails in the following manner. From battery 110 by wire 111, armature 112, wire 114, interrupter 106_x, wire 115, resistance 116, lead 117, rail 1 of block X, across the train to rail 2, lead 118, wire 157, armature 120 and wire 121 back to battery 110. Bridging wires 115 and 118 is the primary 65 122 of a transformer 123_x, the secondary 124 of which is interposed in a rail and ground circuit composed of said secondary wire 125, resistance 126, wire 145 and ground on one side of said secondary; and 70 wire 141, armature 143, wire 144 and wire 118 to rail 2 on the other side of the secondary. Rail 2 is not grounded but may in fact be insulated, that is to say the insulation is of course not perfect and there exists a leakage 75 of current, but not an excessive one, so that voltage above ground potential is maintained on the rail. If the rail was actually grounded it would not be possible to maintain this voltage and consequently the direct 80 pick-up circuit would not receive an impulse. This current will influence the direct pick-up circuit carried by the train. 109 indicates a relay controlling armatures 112 and 120 and this relay is normally deenergized so long 85 as relay 151_x of the succeeding block is energized. But when a train enters block X from block W relay 151_x will be deenergized thereby causing armatures 152 and 143 of relay 151_x to drop. When this occurs a circuit 90 is established through back contact 108_x as follows: battery 110_w, wire 146, wire 155, relay 109, wire 153, back contact 108_w, armature 152_w, and wire 156 back to battery 110_w. This picks up armatures 112 and 120 and es- 95 100

tablishes a circuit through motor 107 α as follows: from battery 110, wire 111, armature 112, wire 114, motor 107 α , wire 157, armature 120 back to battery 110. It also establishes 5 the previously described circuit through interrupter 106 α . Thus when no train is in block X no current to affect either the indirect or the direct pick-up circuit is supplied.

When a train enters block Y and a train 10 K is present in block Z the rail and ground circuit is ruptured owing to the deenergization of relay 151 α and if the train enters block Z with another train already in the block no current will be received by said second train.

In Fig. 2 is shown a trackway system to cooperate with two inductively coupled train carried circuits. In this form of the invention the usual track battery 150 α is connected 20 to rail 1 by wire 160 and to rail 2 by wire 161, coil of relay 162 α and wire 163; track relay 151 α is connected to rails 1 and 2 by leads 164 and 165. The resistance of relay 162 is such that it does not interfere with 25 the proper control of relay 151 α and is so adjusted that normal flow of current will not energize its coils sufficiently to lift armatures 166 and 167, but, when a train enters block X and relay 151 α is shunted the current 30 flow will be sufficiently increased to cause relay 162 α to lift armatures 166 and 167.

In this form of the invention the interrupting means are shown as being of the vibratory armature type and the motor elements are in 35 the form of magnets. Motor element 168 of interrupter or vibrating armature 170 is energized by the following circuit: battery 110 α , wire 169, armature 170, contact point 171, wire 172, coil of 168, wire 173, contact 40 point 174, armature 167 when in lifted position and wire 175 back to battery 110 α . The circuit just traced is normally open or ineffective on account of the normal deenergization of relay 162 α . A normally ineffective or open circuit for supplying current, 45 when a train enters the block, from the source through interrupter 170 to the rails of block X in series is as follows: battery 110 α , wire 169, vibrating armature or interrupter 170, contact 171, wire 172, wire 176, resistance 177, wires 178 and 160, rail 1, train shunt, rail 2, wires 163, 179 and 173, contact 174, armature 167 and wire 175 back to battery 110 α .

50 Motor element 184 of the second interrupter or vibrating armature 181 is energized by the following circuit: battery 110 α , wires 169 and 180, vibrating armature 181, contact point 182, wire 183, coil of 184, wire 55 185, contact 186 of track relay 151 γ , wires 187 and 173, contact 174, armature 167 and wire 175 back to battery 110 α . It will be noted that this circuit is controlled not only by relay 162 α but also by track relay 151 γ 60 of the block in advance, and this circuit is

normally open or ineffective on account of the normal deenergization of relay 162 α and is likewise open when the block (Y) in advance is occupied by a train. A normally open or ineffective circuit for supplying current, when a train enters the block and the block in advance is not occupied, from the source through interrupter 181 to the rails of block X in parallel is as follows: battery 110 α , wires 169 and 180, armature 181, wires 183 and 188, armature 189 of relay 151 γ , wire 191, center tap of resistance 192, rails 1 and 2 in parallel, resistance 193, center tap of same, wire 194, contact 195, armature 166 of relay 162 when in the lifted position and wires 196 and 175 back to battery 110 α .

70 Thus, when a train enters block X, relay 162 α is energized sufficiently to lift its armatures and two interrupted currents are supplied to the rails, one through interrupter 170 to the rails in series and the other through interrupter 181 to the rails in parallel. If the block in advance, Y, is occupied and relay 151 γ is deenergized the current to the rails in parallel is not sufficient, and if a train 75 enters a block that is already occupied by another train the current to the rails in series will be shunted by the train occupying the block and the second train will receive no current from the circuit including the rails 80 in series.

In Fig. 3 is shown a modification in which alternating current is employed. As there 85 shown, a transformer T α , in the case of block X, is used the secondary 292 of which is connected to rails 1 and 2 at the outgoing end of block X and whose primary 294 receives power from line wires 295 and 296, the latter being fed by generator G. Between primary 294 and the transmission line is shown a pole 90 changer 197 which is operated by mechanism, indicated by the dotted line, from a wayside signal as Sy. This part of the system need not be used in connection with the train control circuits and need not, therefore, be described except to say that the wayside signal is of the three position type, and that pole changer 197 is used to reverse the polarity of the normal track circuit current. 293 α indicates a track relay connected to the rails at 95 the ingoing end of block X in a well known manner. V α indicates another transformer, the primary 199 of which is energized as follows: transmission line 296, wire 198, winding 199, wire 200, armature 201 of track relay 100 293 α of block X, back contact 202 and wire 203 to transmission line 295. The circuit just traced is therefore normally ineffective or open. Secondary winding 204 of V α is included in a circuit that includes motor element 105 206 to actuate interrupter or vibrating armature 205, which latter preferably makes use of the vibrating reed principle that is so commonly employed in rectifiers for battery 110 chargers. The vibrating armature or inter- 110

rupter is included in the following circuit: secondary 204, wire 207, armature 208 of track relay 293 γ of the block in advance, contact 209, wire 210, rail 2 of block X, train shunt, 5 rail 1, wire 211, impedance coil 212, wire 213, contact 214, interrupter or vibrating armature 205 and back to secondary 204. Thus whenever a train enters block X and shunts relay 293 α a circuit is closed through primary 10 199 which in turn energizes secondary 204 and an interrupted alternating current is therefore supplied to rails 1 and 2 in series. If, however, the block in advance, Y, is occupied relay 293 γ is deenergized and the circuit 15 remains open.

In Fig. 4 is shown a still further modification of the invention. Here transformer T α supplies current to the rails through back contacts 300 and 301 of relay 302 which latter 20 is normally deenergized. Each block is further provided with an interrupter 303 of the revolving armature type actuated by motor element 304. When a train enters block X and shunts track relay 293 α then relay 302 at 25 the outgoing end of the block will be energized and the following circuit will be established through motor element 304: secondary 305, wire 306, front contact 307, wire 308, motor element 304, wire 309, front contact 310, and wire 311 back to secondary 305. Another circuit through the interrupter will also 30 be established as follows: secondary 305, wire 306, front contact 307, wire 308, interrupter 303, wire 312, rail 1 of block X, train 35 shunt, rail 2, wire 313, front contact 314 and wires 315 and 311 back to secondary 305. If the block in advance, Y, is occupied and relay 293 γ is deenergized then relay 302 will likewise be deenergized so that the circuit through 40 the interrupter to the rails remains open. If a second train enters a block already occupied then this second train will receive no current.

In Fig. 5 a further modification of the invention is shown. Here the track circuit is 45 of the direct current type and is supplied by a battery as 316. When a train enters block X from the right and shunts the track relay then relay 317 at the outgoing end becomes 50 energized and will disconnect track battery 316 from the rails at the back contacts 318 and 319. The energization of relay 317 will close circuits from primary 322 of transformer T α through motor element 320 and interrupter 321 as will be apparent, and will 55 also close a circuit from secondary 323 of transformer T α to the rails. The interrupter will cause an interrupted current to flow in primary 322 and this, in turn, will be induced in secondary 323 and the latter will 60 then supply the interrupted current to the rails by way of the following circuit: secondary 323, wire 324, front contact 325, wire 326, rail 1, train shunt, rail 2, wire 327, front contact 328 and wire 329 back to secondary 65 323. Thus the interrupter included in the cir-

cuit of the primary controls or influences or modifies the current flowing in the secondary.

By the expression "pulsating" current used in the accompanying claims it is intended to comprehend both an alternating or oscillating current or an interrupted or fluctuating direct current, and by an "interrupted" current is meant either a direct or an alternating interrupted current.

The feature of disconnecting the track battery or source from the rails when coded current is being supplied to said rails, and/or the feature of having two paths through which a source or sources of electrical energy may be connected across the track rails, one 75 of which paths is normally closed but which is opened when coded or interrupted current is being supplied over the other path, is not claimed herein but forms the subject matter of a copending application of Edward C. 80 Sasnett Ser. No. 24,544 filed April 20, 1925. So likewise, the specific form disclosed in Fig. 5 hereof is not specifically claimed herein but forms the subject matter of applicant's copending application Ser. No. 516,886 filed 85 February 19, 1931.

I claim:

1. A track circuit system comprising: traffic rails divided into blocks, a source of current, a circuit including both rails of a block, 95 a circuit between ground and at least one of said rails, and an interrupter for supplying an interrupted current to said circuits from said current source.

2. A track circuit system comprising: traffic rails divided into blocks, a source of current, an interrupter connected to said source, 100 a circuit including both rails of a block fed by said interrupter and source, a circuit between ground and at least one of said rails, 105 and a transformer between said first and said second circuit.

3. A track circuit system comprising: traffic rails divided into blocks, a source of current, a circuit including both rails of a block, 110 a circuit between ground and at least one of said rails, means for supplying a pulsating current to said circuits from said current source, and a relay controlled by traffic in a preceding block for controlling the circuit 115 between rail and ground.

4. A track circuit system comprising: traffic rails divided into blocks, a source of current, a circuit including both rails of a block, 120 a circuit between ground and at least one of said rails, an interrupter for supplying an interrupted current to said circuits from said current source, and a relay controlled by traffic in a preceding block for controlling the current between rail and ground.

5. A track circuit system comprising: traffic rails divided into blocks, a source of current, an interrupter connected to said source, 125 a circuit including both rails of a block fed by said interrupter and source, a circuit be-

5 between ground and at least one of said rails, a transformer between said first and said second circuit and a relay controlled by traffic in a preceding block for controlling the circuit between rail and ground.

6. A track circuit system comprising: traffic rails divided into blocks, a source of current, a motor, an interrupter driven by said motor, a circuit including said source and motor but normally ruptured, a circuit including said source, both rails and the interrupter but normally ruptured, and means for completing said circuits when a train enters a block.

10 7. A track circuit system comprising: traffic rails divided into blocks, a source of current, a motor, an interrupter driven by said motor, a circuit including said source and motor but normally ruptured, a circuit including said source, both rails and the interrupter but normally ruptured, a circuit between ground and at least one of said rails, fed from the circuit passing through the interrupter, and means for completing the circuits through the motor and interrupter when a train enters a block.

15 8. A track circuit system comprising: traffic rails divided into blocks, a source of current, a motor, an interrupter driven by said motor, a circuit including said source and motor but normally ruptured, a circuit including said source, both rails and the interrupter, and means for completing the circuit through the source and motor when a train enters a block.

20 9. A track circuit system comprising: traffic rails divided into blocks, a source of current, a motor, an interrupter driven by said motor, a circuit including said motor and source but normally ruptured, a circuit including said source, both rails and the interrupter, a circuit, between ground and at least one of said rails, fed from the circuit passing through the interrupter, and means for completing the circuit through the source and motor when a train enters a block.

25 10. A track circuit system comprising: traffic rails divided into blocks, a source of current, a motor, an interrupter driven by said motor, a circuit including said source and motor but normally ruptured, a circuit including said source, both rails and the interrupter but normally ruptured, a circuit, between ground and at least one of said rails, fed from the circuit passing through the interrupter, means for completing the circuits through the motor and interrupter when a train enters a block, and a relay controlled by traffic in a preceding block for controlling the circuit between rail and ground.

30 11. A track circuit system comprising: traffic rails divided into blocks, a source of current, a motor, an interrupter driven by said motor, a circuit including said source and motor but normally ruptured, a circuit

35 including said source, both rails and the interrupter, a circuit between ground and at least one of said rails, means for completing the circuit through the source and motor when a train enters a block, and a relay controlled by traffic in a preceding block for controlling the circuit between rail and ground.

40 12. A track circuit system comprising: traffic rails divided into blocks, a source of current, a motor, an interrupter driven by said motor, a circuit including said motor and source but normally ruptured, a circuit including said source, both rails and the interrupter, a circuit between ground and at least one of said rails, fed from the circuit passing through the interrupter, means for completing the circuit through the source and motor when a train enters a block and a relay controlled by traffic in a preceding block for controlling the circuit between rail and ground.

45 13. A track circuit system comprising: traffic rails divided into blocks, a normally charged track circuit, a track relay controlled by said track circuit, a source of current, a motor, an interrupter driven by said motor, a circuit including said source and motor but normally ruptured when said relay of the local block is energized, a circuit including said source, both rails and the interrupter, a circuit between ground and at least one of said rails, fed from the circuit passing through the interrupter, and controlled by the track relay of the preceding block.

50 14. A track circuit system comprising: traffic rails divided into blocks, a normally charged track circuit, a track relay controlled by said track circuit, a source of current, a motor, an interrupter driven by the motor, a circuit including said source and motor but normally ruptured when the track relay of the local block is energized, a circuit including said source, both rails and the interrupter also normally ruptured when the track relay of the local block is energized, and a circuit between ground and at least one of said rails fed from the circuit passing through the interrupter and controlled by the track relay of the preceding block.

55 15. A track circuit system comprising: traffic rails divided into blocks, a track battery, leads connecting said battery to the rails, a track relay connected to the rails, a direct current source, an interrupter, a circuit including said source and interrupter connected to the leads from the track battery, a second circuit, controlled by the track relay of the preceding block, connected to one of the leads of the local track battery and to ground, and a transformer between the second circuit and the circuit passing through the interrupter.

60 16. A track circuit system comprising: traffic rails divided into blocks, a track battery, leads connecting said battery to the rails, a track relay connected to the rails, a direct

current source, an interrupter, a circuit, controlled by the track relay of the local block and normally incomplete so long as said track relay is energized, including said source and interrupter and connected to the leads from the track battery, a second circuit, controlled by the track relay of the preceding block, connected to one of the leads of the local track battery and to ground, and a transformer between the second circuit and the circuit passing through the interrupter.

17. A traffic circuit system including: traffic rails arranged in blocks, circuit means, including the traffic rails and an interrupter, normally ineffective to supply current to said rails, a motor, to actuate the interrupter, normally deenergized, and means, to energize the motor with non-interrupted current, and to render the said circuit means effective to supply interrupted current to the rails of a block in response to the entrance of a train into the block.

18. A traffic circuit system including: traffic rails arranged in blocks, circuit means, including the traffic rails and an interrupter, normally ineffective to supply current to said rails, a motor, to actuate the interrupter, normally deenergized, and a track circuit, which when shunted by the entrance of a train into a block, causes the motor to become energized with non-interrupted current and renders the first circuit means effective to supply interrupted current to the rails of said block.

19. A track circuit system including: traffic rails arranged in blocks, a source of current to be connected across the traffic rails at the exit end of the block, a relay for each block which when energized connects said current source to the rails, and circuit means to energize said relay in response to the entry of a train into the block.

20. A track circuit system including: traffic rails arranged in blocks, a source of current to be connected across the traffic rails at the exit end of the block, a relay for each block which when energized connects said current source to the rails, and a track relay at the entrance end of a block which when shunted by the entry of a train into the block energizes said first-mentioned relay.

21. A traffic circuit system including: traffic rails arranged in blocks, circuit means, including the traffic rails and an interrupter, normally ineffective to supply current to the rails of a block, a motor, to actuate said interrupter, a circuit for said motor normally ineffective to energize it, a relay for each block which when energized renders said motor circuit effective to energize the motor and renders the first circuit means effective to supply current to the rails of a block, and other circuit means to energize said relay in response to the entry of a train into the block.

22. A traffic circuit system including: traffic rails arranged in blocks, circuit means, in-

cluding the traffic rails and an interrupter, normally ineffective to supply current to the rails of a block, a motor, to actuate said interrupter, a circuit for said motor normally ineffective to energize it, a relay for each block which when energized renders said motor circuit effective to energize the motor and renders the first circuit means effective to supply current to the rails of a block, and a track relay which when shunted by the entry of a train into the block energizes said first-mentioned relay.

23. A track circuit system including: traffic rails arranged in blocks, a normally closed track circuit for each block including the traffic rails, a source of current and a track relay, another circuit for each block to control the supply of train controlling current across the traffic rails at the exit end of the block, and a second relay for each block, under the control of the track relay of the same block, to open said other circuit when the track relay is energized and to close said other circuit when the track relay is deenergized.

24. In combination, a section of railway track, a normally open circuit including an electromagnetic device, a second circuit controlled by said device for supplying periodically interrupted train governing current to the rails of said section, and means for closing said first circuit when a train enters said section.

25. In combination, a section of railway track, a normally open circuit including an electromagnetic device, a second circuit controlled by said device for supplying periodically interrupted train governing current to the rails of said section, a track circuit including a track relay for said section, and means for closing said first circuit when said track relay is deenergized.

26. In combination, a section of railway track, a track circuit including a source of current and a track relay for said section, a normally open circuit including a back contact of said track relay and an electromagnetic device, and a third circuit controlled by said device for supplying periodically interrupted train governing current to the rails of said section.

Signed at Pittsburgh, in the county of Allegheny, and State of Pennsylvania, this 1st day of February, 1927.

ARBA G. WILLIAMSON.
